BUILDING CONSTRUCTION

George C. Reid, Rome, N. Y.

Application July 25, 1933, Serial No. 682,090

6 Claims. (Cl. 72—16)

This invention relates to building construction and, more particularly, to improved means for securing metal sheathing to a masonry or other type of wall structure.

It is one of the objects of the invention to provide means for securing metal sheathing to a wall structure so that the sheathing will be adequately supported at frequent intervals and also prevented from buckling as a result of expansion and contraction due to changes in temperature.

A further object of the invention is to provide a method of securing metal sheathing to a wall that will be water-tight and relatively simple and inexpensive in its application.

15 A further object of the invention is to provide an improved method of securing metal sheathing to a masonry wall that will not only possess the above mentioned characteristics but will also provide an exterior surface that will be novel in appearance and conform to the architectural trend in modern building construction.

Other objects of the invention and the features of novelty will be apparent from the following description, taken in connection with the accompanying drawing, of which

Figure 1 is a fragmentary side elevation of a wall structure embodying my invention, a portion of the sheathing being broken away;

Fig. 2 is an enlarged detail section on the line 30 2—2 of Fig. 1;

Fig. 3 is a view similar to Fig. 2 but showing the arrangement of the sheathing prior to forming the lock seam in the edges of the panels;

Fig. 4 is an enlarged detail section on the line 35 4—4 of Fig. 1, and

Fig. 5 is a view similar to Fig. 2 but illustrating the application of the invention to a wall made of lumber.

Referring to Figs. 1 to 4 of the drawing, 10 indicates a masonry wall built up of units, such as cement blocks or bricks with the usual mortar joints. Heretofore much difficulty has been experienced in applying metal sheathing, such as copper, to a wall of this kind so that it will be held tightly against the wall surface and also free from buckling, as a result of expansion and contraction of the metal due to changes in the atmospheric temperature.

In the practice of my invention, I embed heavy-gauge steel strips 11 in the horizontal joints between the wall units. These horizontal strips 11 are vertically spaced in accordance with the spacing between the joints of the wall and the width of the metal panels that are to be used, but 55 a satisfactory vertical spacing of the strips 11

would be approximately twelve inches. The strips 11, as shown in Figs. 2 and 3, extend into the joints a sufficient distance to be firmly anchored therein and project from the face of the wall a distance which is variable, but which I prefer to make approximately one inch and, in order that the strips 11 may have the requisite stiffness, I prefer to use #10 gauge steel.

At intervals along the strips 11, I provide flexible metal tongues 12, preferably of copper and about two inches wide, and these tongues extend into the joints between the wall units a sufficient distance to be firmly anchored therein and, in order to have a secure anchorage, the tongues may be crimped or corrugated as shown at 13. 70 These tongues also are of sufficient length to project beyond the outer edges of the strips 11 a sufficient distance to be interlocked in the seam between the panels of the sheathing, which will be later described in detail.

Between the successive strips 11, I place the panels of the sheathing material, such as copper. These panels may be of any desired length and, for the sake of economy, it is usually desirable to employ standard commercial lengths, such as six 80 or eight feet. These panels are indicated at 14 and have outwardly projecting flanges 15 along their longitudinal edges. As will be seen from Fig. 2, the flange on the lower edge of the panel 14 rests upon the strip 11 and the flange on the upper edge of the panel will abut against the underside of the strip 11 which is immediately above. The strips 11 thus support the weight of the panels and there is no tendency for the portion of the panels which is against the wall surface 90 to separate therefrom.

As the panels are initially positioned on the strips 11, the flanges on the panels are arranged substantially as shown in Fig. 3, with the edges of the flanges projecting beyond the edge of the strip 11 a sufficient distance to permit these edges to be folded into the double lock-seam illustrated at 16 in Fig. 2. In forming this double lock-seam, the tongues 12 are folded into the seam and thus the flanges of the panels are held against outward 100 movement on the strips 11 and away from the wall surface. By forming the double lock-seam as shown in Fig. 2, a weather-proof joint is obtained without the necessity of soldering and the steel strips 11 will thus be thoroughly protected 105 and the structure will last indefinitely.

While I prefer to arrange the double lock-seam 16 along the outer edge of the strip 11 and substantially in the plane of the strip, this is not essential and other types of seams, common in 110

sheet metal work, may be used and the seams may be located wherever desired on the projecting portion of the strips 11.

In order to permit vertical expansion of the 5 panels 14, without buckling, one or both of the corners 17 between the flanges of the panel and the body thereof may be spaced slightly away from the strip 11 and the arrangement of the flanges 15 and the tongues 12, which are not directly attached to the strip 11, permits the flanges to expand both laterally and longitudinally without distorting the body portion of the panel which is against the wall surface.

In the form of the invention illustrated in Fig. 5, 15 the wall is made of boards or planks 18 of natural wood or artificial lumber and the panel-supporting strips 19 are bent into the form of an angle section with the vertical leg on the inner side of the boards 18 and secured thereto by nails 20, screws or any other suitable means. The tongues 21, which are for the same purpose as the previously described tongues 12, have their inner ends bent against the inner side of the boards 18 and nailed or otherwise secured thereto as shown at 25 22. The panels 23 are then laid and secured in position as previously described.

While I have illustrated and described what I now consider to be the preferred embodiment of my invention, it will be apparent that various 30 changes may be made in the details of construction and arrangement without departing from the spirit of the invention which is defined in the appended claims.

Having thus described my invention, I claim:

- 35 1. In building construction, a wall, a plurality of spaced strips secured to said wall, flexible metal tongues spaced at intervals along said strips and secured to said wall, panels of metal sheathing on said wall between said strips and provided with flanges on their opposite edges abutting the strips, and the flanges of said panels on opposite sides of each of said strips being joined together and to said tongues along the outer edge of the strip.
- 40 2. In building construction, a wall, a plurality of spaced strips secured to said wall, flexible metal tongues spaced at intervals along said strips and secured to said wall, panels of metal sheathing on said wall between said strips and provided with flanges on their opposite edges abutting the strips, and the flanges of said panels on opposite sides of each of said strips being folded into interlocking arrangement and having said tongues interlocked therewith.
- 45 3. In building construction, a wall, a plurality

55

of spaced strips secured to said wall, flexible metal tongues spaced at intervals along said strips and secured to said wall, panels of metal sheathing on said wall between said strips and provided with flanges on their opposite edges abutting the strips, and the flanges of said panels on opposite sides of each of said strips being folded into interlocking arrangement along the outer edge of the strip and in the plane of the strip and having said tongues secured thereto.

80

4. In building construction, a masonry wall having horizontally arranged joints between the units of which the wall is constructed, relatively heavy-gauge metal strips embedded in said joints and projecting from the face of the wall, flexible metal tongues fixed with respect to said wall and projecting transversely of said strips, metal panels positioned on said wall and having outwardly turned flanges on their horizontal edges engaging said strips, the flanges on the opposite sides of each strip having their edges interlocked, and the outer ends of said tongues being folded into the interlock between said edges.

85

5. In building construction, a masonry wall having horizontally arranged joints between the units of which the wall is constructed, relatively heavy-gauge metal strips embedded in said joints and projecting from the face of the wall, flexible metal tongues embedded in said joints and projecting transversely of said strips, metal panels positioned on said wall and having outwardly turned flanges on their horizontal edges one of which rests on one of said strips and the other of which engages the under side of the strip next above, the flanges on the opposite sides of each strip having their edges folded together into interlocking arrangement along the edge of the strip, and said tongues being folded into the interlock between said edges.

90

6. In building construction, a wall comprising boards arranged with spaced parallel openings therebetween, spaced members of angle section projecting through said openings and outwardly from the outer side of said boards and having one leg secured against the inner side of the boards, flexible tongues secured to said boards and projecting outwardly therefrom, panels of metal sheathing on said wall between said members and provided with flanges on their opposite edges abutting said members, and the flanges of said panels on opposite sides of each of said members being folded into interlocking arrangement and having said tongues interlocked therewith.
